(57) **CLAIM**

We claim the ornamental design for charger for mobile phone, as shown and described.

DESCRIPTION

FIG. 1 is a front/right side/top perspective view of a charger for mobile phone showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front/right-side/top perspective view thereof showing the aspect when this charger is connected to mobile phone and plug.

The broken lines are included for the purpose of illustrating environmental structure and form no part of the claimed design. The dash-dot break line shown on the cable in FIGS. 1-5 and 8 represents that the claim is not directed to a particular length of cable.
